TUBULAR INTERRUPTER ENCLOSED IN
BUS HOUSING

Fred L. Kradel, Greensburg, Pa., assignor, by
mesne assignments, to I-T-E Circuit Breaker
Company, Philadelphia, Pa., a corporation of
Pennsylvania

Application February 15, 1951, Serial No. 211,133

16 Claims. (Cl. 200—146)

1

My present invention relates to interrupters of the type generally disclosed in Patent No. 2,383,-795 and more particularly to a tubular interrupter adapted to open a circuit under load and extinguish the arc formed during the interruption while at the same time the interrupter is arranged so that all of the interrupting operations, as well as reclosure after interruption, can be accomplished by a single longitudinal motion in appropriate sequence.

More particularly, my invention relates to an interrupter particularly adapted for inclusion in a bus run, preferably in an isolated phase bus enclosure, although, of course, it is adapted for use in segregated phase bus enclosures as well as in connection with bus runs which are otherwise enclosed or not enclosed at all.

Essentially my novel interrupter comprises a tubular member interconnecting a pair of opposite terminals with the end of the tube. One of the terminals carries a main contact which is circular in cross-section or at least substantially circularly arranged in a plane transverse to the plane of movement of the operating parts of the interrupter.

The movable member of the interrupter has a corresponding circular main contact engaging the stationary main contacts. The stationary contact is essentially an external contact around the outside of a tube, while the main contact engaging therewith is essentially an internal contact around the periphery of a sliding tube. The stationary contact has in parallel therewith a stationary arcing contact which is also annular and which is mounted on the inside of a tube extending from the main stationary contact.

The exterior of the tube extending from the main stationary contact is of insulating material, while the interior is of conductive material in order to establish a connection between the main stationary contact and the stationary arcing contact.

An arcing contact plunger with an arc extinguishing follower of gas evolving or other appropriate deionizing material is mounted on the inside of the tubular extension from the main stationary contact with means being provided to releasably latch the movable arcing contact plunger against movement.

The movable arcing contact plunger is arranged so that on movement away from the main stationary contact of the tube carrying the main movable contact, the movable arcing contact plunger is increasingly spring biased toward

55

The primary object of the present invention is

2

movement to a position where the arcing contacts will separate.

However, the releasable latch prevents movement to open position of the arcing contacts until the spring is fully compressed whereupon the arcing contact plunger is snapped out of its retaining means drawing an arc between the stationary arcing contact and movable arcing contact, the arc being confined in an annular chamber of small cross-section defined by the follower as the inner wall of the chamber and a tubular arc resistant insert as the outer wall of the chamber.

This last operation snaps the plunger back to substantially inside the movable tubular member. During the opening movement of the main contact as well as during the tensioning of the opening bias for the arcing contact, the movable tubular member hereinbefore described was latched to a second movable tubular member, being connected thereto primarily by a pair of sets of interengaged annularly arranged contacts, the second tubular member being arranged for current carrying connection with the terminal on that side.

25 Immediately after the plunger for the movable arcing contact is released so that the arc is drawn and the circuit interrupted, the engagement between the contacts of the first-mentioned tubular member and the second-mentioned tubular member is released. Consequently, the opening operation is performed by moving the second-mentioned tubular member away from the main stationary contact, thereby drawing the first-mentioned tubular member with it.

30 The first step in the operation opens the main contacts but retains the by-pass circuit through the arcing contacts. At the second step in the operation, the arcing contacts open interrupting the circuit.

35 Immediately after the operation of the latch release mechanism, continued movement of the second-mentioned tubular member results in disengagement of the contacts between the first-mentioned and second-mentioned tubular members so that further movement of the second-mentioned tubular member in the opening direction serves to create an additional circuit opening, the circuit in the open condition of the switch

40 being broken at two points in series, one of the points having an air gap between and the other of the points having an insulating sleeve between the opposite contacts.

the provision of a novel circuit interrupter adapted primarily for use in bus runs.

Another object of the present invention is the provision of a circuit interrupter adapted for inclusion in a bus housing.

Another object of the present invention is the provision of a circuit interrupter which is essentially tubular or longitudinal in construction and operates primarily on longitudinal movement alone.

Another object of the present invention is the provision of a novel arrangement to obtain a plurality of series breaks in the circuit when the circuit interrupter is in the open position.

Another object of the present invention is the provision of novel means for securing together automatically releasing contact elements progressively during the opening movement of the circuit interrupter.

The foregoing and many other objects of my invention will become apparent in the following description and drawings in which:

Figure 1 is a top plan view partly broken away showing the manner in which my novel circuit interrupter may be mounted in isolated phase bus housings for interconnection of longitudinal bus runs.

Figure 2 is a side view of the interrupter of Figure 1 showing the same in closed position, taken on line 2—2 of Figure 1.

Figure 3 is a side view of the interrupter of Figure 1 showing the same in open circuit position.

Figure 4 is a cross-sectional view taken from line 4—4 of Figure 2 looking in the direction of the arrows and showing the arrangement of the elements in my novel circuit interrupter in the closed circuit position.

Figure 5 is a view similar to that of Figure 4 showing the intermediate position of my novel circuit interrupter during opening, at which time the arcing contact plunger opening means is being prepared for opening and just prior to the arc interruption.

Figure 6 is a view corresponding to that of Figures 4 and 5 showing the condition immediately after the arc interruption has occurred and just as the operating tube is released from the movable contact tube to create an additional series break in the open circuit condition of my novel circuit interrupter.

Figure 7 is a cross-sectional view taken on line 7—7 of Figure 4 looking in the direction of the arrows and showing the means for releasing the latching engagement between the second tubular member and the first tubular member and also the method of establishing contact for the by-pass circuit through the arcing contacts.

Figure 8 is a view partly in cross-section taken from line 8—8 of Figure 1 looking in the direction of the arrows and showing a portion of the opening means for my novel circuit interrupter.

Figure 9 is a cross-sectional view taken from line 9—9 of Figure 8 looking in the direction of the arrows.

Figure 10 is a cross-sectional view taken on line 10—10 of Figure 8 looking in the direction of the arrows.

Figure 11 is a cross-sectional view taken on line 11—11 of Figure 8 looking in the direction of the arrows.

Referring now particularly to Figure 1 as well as to Figures 2 and 3, my novel circuit interrupter 20 is here shown as a one pole interrupting switch in the isolated phase housing 21 of a bus run

comprising isolated phase housings 22, 21 and 23.

It will be obvious that the method of connection here shown will permit the utilization of a two or three or more pole interrupter which is simultaneously operated by the same operating mechanism and for most purposes, of course, the number of poles in the interrupter for simultaneous operation will equal the number of bus runs at the particular location; the description, however, of the operation of one of the poles will suffice to make clear the operation also of a multi-pole unit.

The terminal 25 is mounted between insulators 26 and 27, being secured thereto in any suitable fashion, for instance, by bolts 28 passing through extensions 29 of the U-shaped bracket 30 which supports the terminal. Bolts 31 serve to secure the terminal 25 to the base of the U-shaped bracket 30. Insulators 26 and 27 are supported structurally at their outer ends by the channel beams 32, 32 which serve also to support the walls 33 of the bus enclosure 21.

Tubular conducting bar 35 is mounted on terminal 25, being rigidly supported at one end by the terminal 25 and the bracket 30. Tubular member 40 is slidably mounted on tubular member 35, the tubular member 40 being the "second-mentioned" tubular member hereinbefore referred to before the specific description of the individual figures.

Tubular member 40 is latched to tubular member 41 in current conducting relation therewith, the said tubular member 41 being the "first-mentioned" tubular member hereinabove referred to prior to the specific description of the figures. Tubular member 41 rides over the insulating tube 42 where the contact fingers 43 of the tubular member 41, in the closed circuit position of the interrupter, engage the annular contact ring 44 which in turn is mounted on U-shaped bracket 30a having a construction and manner of support in the bus enclosure 21 identical with the U-shaped bracket 30 and carrying the opposite terminal 25a which may be connected in any suitable manner as by the pigtail 45 and bar 46 to a bus. Terminal 25 may also be connected in a similar manner to a bus.

Each of the housings 21, 22, 23 are structurally supported and reinforced by the beams 32. Partitions 40 included in each of the enclosures 21 to 23 to segregate various sections of each isolated phase enclosure and spacer bolts 51 may be provided between adjacent walls of adjacent isolated phase bus enclosures to strengthen the walls and also strengthen the individual buses against deflection owing to magnetic forces which may occur at high currents.

The above referred to second-mentioned sliding tube 40 is supported for sliding movement between rollers 53, 54 carried on insulators 55 and 56. The support for the sliding tube 40 permits the sliding tube 40 itself to support the outer or initially unsupported end of conductor bar 35.

The above referred to first-mentioned sliding tube 41 is similarly supported by rollers 60 and 61 carried, respectively, by insulators 62 and 63, the left-hand end of the sliding tube 41 riding over the insulating tube 42 serving also to support the outer or right-hand end of insulating tube 42 (with respect to Figure 3).

Reference should now be made to Figure 4 as well as to Figures 1, 2, and 3.

It is sufficient for the moment to point out that mechanical means are provided for moving

the tube 35 in a longitudinal direction toward the right with respect to Figures 1 to 4 for the opening movement and to the left with respect to Figures 1 to 4 for the closing movement and that the same operating mechanism may be used simultaneously to operate a multi-pole interrupter each individually enclosed in the isolated phase housing of a multi-phase bus.

Terminal 25a as previously pointed out carries the main stationary contact 44 which has an external annular contact surface. The interior of stationary contact 44 is provided with the annular recess 70 for retention of garter spring 71 which as hereinafter described will act as the yieldable or releasable latching means for the movable arcing contact plunger.

The recess 70 communicates with the internally threaded counterbore 73 at the right end of the main contact 44. Conducting tube 80 having the threaded end 81 is screwed into the internally threaded recess 73, thereby providing a retaining surface 75 for holding the garter spring 71 in place and providing, of course, a conductive extension for the contact 44.

The right-hand end of conducting tube 80 is provided with an annular recess 83 for retention of the stationary arcing contact 84 and has further or beyond the recess 83 the internal thread 85 into which the threaded end 86 of insulating tube 87 may be screwed as an extension of the conducting tube 80, the left-hand end surface 90 of the tube 87 forming a retaining flange for the stationary arcing contact 84.

The interior conducting tube 80 adjacent the right-hand end thereof is counterbored to a somewhat increased diameter at 92 to receive the insulating tubular insert 93 which is supported between the left-hand annular surface 94 on one side and the stationary arcing contact 84 on the other side. The outermost right-hand end of insulating tube 87 is externally threaded at 95 to receive and support the nut 96 which is also of insulating material, the nut 96 being provided as seen particularly in Figure 7 with four equally spaced radial openings 97 receiving the set screws 98, the set screws 98 extending out beyond the periphery of nut 96 to act as a latch release member to permit separation of the first-mentioned tube 41 and the second-mentioned tube 40 at the end of the opening operation.

The right-hand end of insulating tube 86 beyond the threaded section 95 which supports the nut 96 has secured thereto in any suitable manner the metallic exhaust sleeve 100 carrying annularly arranged about the right-hand face 101 thereof the U-shaped brushes 102 as seen particularly in Figures 6 and 7.

The U-shaped current carrying brushes 102 serve to conduct the arcing current from the plunger to the tube 40 in the manner herein-after described.

The wall of metallic tube 100 is provided with a plurality of circumferential openings having appropriate metallic screens to serve as a flame extinguishing exhaust passage for arc gases when the arc is drawn and extinguished in the manner hereinafter described.

All of the elements thus far described are stationarily secured to the main stationary contact 44 and hence to the left-hand terminal 25a. The interior of conducting tube 80 provides a chamber 110 which essentially is for the purpose only of receiving the follower 112 as hereinafter described the chamber 110 communicating with the arc extinguishing chamber 111 to the right of the

stationary arcing contact 84 which is formed by the interior wall of insulating tube 87 and the exterior wall of follower 112 which, of course, is of insulating material, the chamber 111 being, of course, of annular cross-section.

The tube 41 is a conducting tube which is provided with an externally threaded recess section 120 at the left-hand end. The main movable contact 43 is a cylindrical internally threaded member which is screwed onto the threaded extension 120 to establish a firm current carrying engagement therewith.

The cylindrical member 43 is slotted at 125, 125 to produce a plurality of contact fingers 126 having contact buttons 127 at the ends thereof making contact with the main stationary contact 44. The main copper tube 41 is provided with longitudinal slots 130 as shown in the views of Figures 4 to 6 and especially in Figure 7.

Set screws 98 project into the slots 130. The main copper tube 41 is provided also with an auxiliary external stainless steel tube 132 secured to the tube 41 by bolts 133. Between the latch finger tube 132 and the main tube 41 is provided the latch releasing tube 135 having the longitudinal slots 136 which essentially match with longitudinal slots 130 in the main tube 41.

The external tube 132 is slotted at 140 to produce a plurality of latching fingers 141 each having a latching detent 142 and each having the internal chamfered surface 143. The latch releasing tube 135 is provided with a correspondingly chamfered end 144 so arranged that when the latch finger tube 132 moves to the right with respect to the latch releasing tube 135, the latching fingers 141 will be spread apart.

The second tube 40 is provided with a plurality of contact fingers 150 defined by longitudinal slots 151, the contact fingers 150 having contact buttons 152 engaging the series contact member 153 which is a cylindrical member in electrical contact and in threaded relation at 154 with the right-hand end of the main tube 41.

When tubes 40 and 41 are interconnected and the interrupter switch is closed, it will be seen that latching detents 142 of latching fingers 141 engage the ledges 156 on contact fingers 150 to retain the interlock between tubes 40 and 41.

During the opening movement, set screw 98 as hereinafter described acts to stop latch releasing tube 135, thereby causing the latch finger tube chamfered surfaces 143 of latch fingers 141 to be drawn over the chamfer 144 on the latch releasing tube 135, releasing the latches as shown in Figure 6 and permitting tube sections 40 and 41 to separate as shown in Figure 3.

The series contact member 153 which, as above pointed out, is a cylindrical unit screwed into the right-hand end of main tube 41 is provided with the central internally threaded support 160 which stationarily secures with respect to contact 153 the operating rod 162 for the movable arcing contact plunger.

Operating rod 162 extends through opening 163 into the sliding cylindrical copper plunger 164, the said plunger 164 having the internal chamber 165, the right-hand wall 166 containing opening 163 and a plug 167 at the left-hand wall which plug is of copper and carries the movable arcing contact 170 and is also secured by screw 171 in the insulating follower 112.

Compression spring 180 or a plurality of such compression springs as indicated by the addition of compression spring 181 is mounted inside chamber 165 of plunger 164 between the wall

166 of chamber 165 and nut 185 secured on the end of operating rod 162.

Follower 112 is provided at its left-hand end with the latching detent 190 engaged by garter spring 71 in recess 70. In the closed position of the circuit interrupter, current passes from main stationary contact 44 to contact buttons 127 on contact fingers 126 of the main movable contact 43.

Current then passes through the main copper body of tube 41 to the series contact 153 and then through contact fingers 150 at the end of copper tube 40 into the copper tube 40 and then through the additional series contact 200 comprising a plurality of contact fingers 201 to the copper tube 35.

Since copper tube 35 is connected to terminal 25 and main stationary contact 44 is connected to terminal 25a, this current path establishes a full low loss current carrying passage between the two terminals.

When now tube 40 is drawn to the right by the means hereinafter described in order to open the circuit, because of the connection by means of detents 156 and latches 142 between tube 40 and tube 41, tube 41 is also drawn to the right. This results in the movement of contact 153 to the right since contact 153 is a part of the tube 41, thereby maintaining the engagement between contact fingers 150 of tube 40 and contact 153 of tube 41. This also results in pulling operating rod 162 for plunger 165 to the right.

At the same time, the main contacts 44 and 43 are opened since contact 43 slides to the right with tube 41 while contact 44 is stationary at terminal 25a.

Consequently, the contact buttons 127 of contact fingers 126 of contact 43 slide off the main contact 44 and over the insulating tube 42.

A current path as seen in Figure 5 is nevertheless maintained at this time between terminal 25a and terminal 25 despite the fact that engagement between contacts 44 and 43 is broken.

Current now passes through the by-pass from the interior contact 44 to the copper tube 80 to the stationary arcing contact 84 to the wall of plunger 165 and from the wall of plunger 165 through the U-shaped brush 102 to the interior wall of tube 41 and then to the series contact 153, the contact fingers 150, the tube 40, the contact fingers 201, the tube 35 to the terminal 25.

This current path existed initially as will be seen from a comparison of Figures 4 and 5 even when the interrupter was in closed circuit position and, of course, existed in parallel with the principal current path.

However, on the initiation of the opening movement and on separation of contacts 44 and 43, this last-mentioned current path becomes the only current path through the interrupter.

As now the tubes 40 and 41 continue their movement to the right, springs 180 and 181 are continuously compressed and thereby increase the bias to the right on wall 166 of plunger 164 until the springs 180 and 181 are fully compressed and now act as a solid bar.

At this time, continued opening movement to the right of tube 40 pulling on tube 41 through rod 162 pulls the chamber 164 to the right and snaps the latching detent 190 of the follower 112 out from the latching garter spring 71 to permit an extremely rapid opening movement to the right of plunger 164 and the follower 112.

As the movable arcing contact 170 passes the stationary arcing contact 84, an arc is drawn

between them and extinguished in the narrow annular passage 111 between the tube 81 and follower 112, this annular passage being substantially just enough to provide for mechanical clearance between follower 112 and tube 81 and providing an efficient arc extinguishing medium.

Any exhaust gases may now exit through the wall of the screened tube 100 as previously mentioned.

Just after this opening movement of the arcing contact occurs, on further slight continuation of movement of tube 40 to the right pulling along tube 41, the slot 136 in intermediate release tube 135 moves to a position where its end abuts against set screw 98.

As previously mentioned, there are a plurality of such set screws and hence a plurality of such slots. This abutment of the left-hand end of slot 136 in intermediate tube 135 against the set screw 98 causes the intermediate tube 135 to move to the left with respect to the main tube 41 as seen by a comparison of Figures 5 and 6 and notably an examination of the difference in clearance at point 210 of Figure 5 and 210a of Figure 6.

Actually, of course, the tube 135 is caused to remain stationary by the set screw 98 with the insulating tube 42, but the net effect is to cause a movement to the left with respect to the main tube 41 which at the moment is moving to the right. This pulls the chamfered surface wedge-shaped latch releasing annular section 144 against the chambered surface 143 of latch fingers 141 releasing the latching detents 142 from the latching detents 156 on the contact fingers 150 and now permitting the tube 40 to move further to the right clear of tube 41 as shown in Figure 3 to provide an additional series separation for the circuit.

Thus, in moving from the closed to the open position, first the main contacts separate. Second, the arcing contact is tensioned for rapid opening (see Figure 5). Third, the arcing contacts separate (see Figure 6), and immediately after the circuit is additionally broken in series across an air gap by separation of contacts 153 and 150.

In order to close the circuit, tube 40 is driven to the left. The ends of contact fingers 150 strike against the end of tube 41, pushing it to the left. The end of nut 160 pushes against wall 166 of chamber 164 pushing it to the left and hence pushing the follower 112 to the left so that there is a solid force behind the follower 112, thereby serving to drive the chamfered surface 200 at the end of the follower in a direction to spread the garter spring 71 and permit it to engage in the latching detent 190.

At the same time, of course, movement of tube 41 to the left results in interengagement of contacts 43 and 44.

It is obvious that any suitable means may be provided for operating the tubular interrupter of the present invention and that essentially such means must be arranged so that it will provide a simplified mechanical means for driving tube 40 alone to the left for closing and to the right for opening, the operation of tube 40 alone causing all of the other elements to operate as above described.

Consequently, in Figure 1 (see also Figures 2 and 3) as well as in Figure 8 I have shown one method of achieving this result.

Tube 40 is provided with a pair of bracket arms 300 secured in any suitable manner thereto and

carrying the bracket 301. Pinion 302 mounted on shaft 303 will move the rack 301 back and forth and hence tube 40 back and forth in accordance with rotation of shaft 302.

Shaft 302 is supported between rotatable insulators 305, 306 supported in turn in the side walls of a bus housing or enclosure. Insulator 305 is connected by coupling 307 to an appropriate insulated shaft 308 or to another pair of rotatable insulators in series in housing 22 which in turn are rotatably connected to shaft 310, the essential element being that shaft 303 be broken into insulated or electrically isolated sections so that no current carrying path for grounding or short circuiting the device will exist along the shaft 303.

The composite shaft 303, 305-310 is connected by bevel gear 312 to bevel gear 313 on shaft 314 which in turn is connected by bevel gears 316 and 317 to shaft 318 which in turn is connected by bevel gears 319 and 320 to crank shaft 323 having the crank handle 324.

Rotation of the crank handle 324 in one direction will rotate the various shafts in a corresponding direction to move the interrupter to the open position and reverse rotation will rotate the shafts in a corresponding direction to move the interrupter to the closed position.

The shafts 318, 323 are carried in a suitable housing having a front wall 331 and a back wall 331a provided with appropriate lugs 332 for securing to appropriate support. Shaft 318 has a pair of collars 330, 340 secured thereto having a plurality of spaced openings 341 and peripheral recesses 342 as seen in Figures 8 and 9.

A stop member 345 is carried by the back wall 331a of the machine, the stop member having slidably supported thereon the slide bar 346. The slide bar 346 is an extension of nut 348 mounted on threaded section 349 of shaft 318. Rotation of shaft 318 causes the nut 348 to move longitudinally of shaft 318 owing to the fact that the interengagement of slide 346 with bar 345 prevents rotation thereof.

A forward extension 340 of nut 348 carries a pointer 351 which is slideable through window 352 (see Figures 8 and 10) to indicate the open and closed position of the interrupter. Set screws 341a, 341a locked in openings 341 of collars 340 on opposite sides of the slide bar 346 serve to act as stops for the rotation in either direction.

In addition, slide bar 346 is provided with extensions 360, 360 which enter the notch 342 adjacent the stop pin 341a to prevent any accidental rotation of shaft 318.

Handle 324 is provided with the padlock disc 370 having a plurality of openings 371 adjacent the periphery thereof registering with an opening 372 in stationary bar 373. The hasp 374 of padlock 375 may be slipped through registering openings as seen in Figures 8 and 11 to maintain the interrupter in the open or closed position as the case may be against unauthorized tampering.

In the foregoing I have described my invention solely in connection with specific illustrative embodiments thereof. Since many variations and modifications of my invention will now be obvious to those skilled in the art, I prefer to be bound not by the specific disclosures herein contained but only by the appended claims.

I claim:

1. Switch gear extending longitudinally along a principal axis and comprising a movable main contact, a movable arcing contact, a movable disconnect contact and complementary contacts

for each of said movable contacts; said movable contacts being operable along said principal axis; said main contacts and arcing contacts being in parallel when in closed position, said disconnect contact being in series with said main and arcing contacts when in closed position, a latch for said arcing contacts and biasing means operative following release of said latch for operating said arcing contacts to open position at high speed.

2. Switch gear extending longitudinally along a principal axis and comprising a movable main contact, a movable arcing contact, a movable disconnect contact and complementary contacts for each of said movable contacts; said movable contacts being operable along said principal axis; said movable contacts being operable from closed to open position in a predetermined sequence with the main contact opening first, the arcing contact opening next and the disconnect contact opening last, a latch for said arcing contacts and biasing means rendered effective to release said latch and operate said contacts to open position at high speed.

3. Switch gear extending longitudinally along a principal axis and comprising a movable main contact, a movable arcing contact, a movable disconnect contact and complementary contacts for each of said movable contacts; said movable contacts being operable along said principal axis; said main contacts and arcing contacts being in parallel when in closed position, said disconnect contact being in series with said main and arcing contacts when in closed position; said movable contacts being operable from closed to open position in a predetermined sequence with the main contact opening first, the arcing contact opening next and the disconnect contact opening last, and biasing means connected to said arcing contacts and operative to provide snap action for opening of said arcing contacts.

4. Switch gear extending longitudinally along a principal axis and comprising a movable main contact, a movable arcing contact, a movable disconnect contact and complementary contacts for each of said movable contacts; said movable contacts being operable along said principal axis; said main contacts and arcing contacts being in parallel when in closed position, said disconnect contact being in series with said main and arcing contacts when in closed position; said movable contacts being operable from closed to open position in a predetermined sequence with the main contact opening first, the arcing contact opening next and the disconnect contact opening last, and an arc extinguishing chamber extending longitudinally along said principal axis, and biasing means connected to said arcing contact and operative to provide high speed opening of said arcing contact.

5. Switch gear extending longitudinally along a principal axis and comprising a movable main contact, a movable arcing contact, a movable disconnect contact and complementary contacts for each of said movable contacts; said movable contacts being operable along said principal axis; said main contacts and arcing contacts being in parallel when in closed position, said disconnect contact being in series with said main and arcing contacts when in closed position; said movable contacts being operable from closed to open position in a predetermined sequence with the main contact opening first, the arcing contact opening next and the disconnect contact opening last, and an arc extinguishing chamber extending longitudinally along said principal axis, and an

insulating follower extending from said arcing contact through said arc extinguishing chamber along said principal axis.

6. Switch gear extending longitudinally along a principal axis and comprising a movable main contact, a movable arcing contact, a movable disconnect contact and complementary contacts for each of said movable contacts; said movable contacts being operable along said principal axis said main contacts and arcing contacts being in parallel when in closed position, said disconnect contact being in series with said main and arcing contacts when in closed position; said movable contacts being operable from closed to open position in a predetermined sequence with the main contact opening first, the arcing contact opening next and the disconnect contact opening last, and an arc extinguishing chamber extending longitudinally along said principal axis, an insulating follower extending from said arcing contact through said arc extinguishing chamber along said principal axis, and a member carrying said main movable contact; said member housing said arcing contacts and arc extinguishing chamber.

7. Switch gear extending longitudinally along a principal axis and comprising a movable main contact, a movable arcing contact, a movable disconnect contact and complementary contacts for each of said movable contacts; said movable contacts being operable along said principal axis; said main contacts and arcing contacts being in parallel when in closed position, said disconnect contact being in series with said main and arcing contacts when in closed position; said movable contacts being operable from closed to open position in a predetermined sequence with the main contact opening first, the arcing contact opening next and the disconnect contact opening last, and an arc extinguishing chamber extending longitudinally along said principal axis, an insulating follower extending from said arcing contact through said arc extinguishing chamber along said principal axis, and a member carrying said main movable contact, said member housing said arcing contacts and arc extinguishing chamber, said movable disconnect contact when engaged with its complementary contact being in latched engagement with said last-mentioned member; the complementary contact for the disconnect contact being mounted on said member.

8. Switch gear extending longitudinally along a principal axis and comprising a movable main contact, a movable arcing contact, a movable disconnect contact and complementary contacts for each of said movable contacts; said movable contacts being operable along said principal axis; said main contacts and arcing contacts being in parallel when in closed position, said disconnect contact being in series with said main and arcing contacts when in closed position; said movable contacts being operable from closed to open position in a predetermined sequence with the main contact opening first, the arcing contact opening next and the disconnect contact opening last, and an arc extinguishing chamber extending longitudinally along said principal axis, an insulating follower extending from said arcing contact through said arc extinguishing chamber along said principal axis, a member carrying said main movable contact, said member having its main axis coinciding with said principal axis; said member housing said arcing contacts and arc extinguishing chamber, said movable disconnect contact when engaged with its complementary contact being in latched engagement with said last-mentioned member.

mentary contact being in latched engagement with said last-mentioned member; the complementary contact for the disconnect contact being mounted on said member; and operating mechanism connected to and moving said movable disconnect contact and being operable through said latch mechanism to draw said last-mentioned member toward open circuit position at said main contacts.

9. Switch gear extending longitudinally along a principal axis and comprising a movable main contact, a movable arcing contact, a movable disconnect contact and complementary contacts for each of said movable contacts; said movable contacts being operable along said principal axis; said main contacts and arcing contacts being in parallel when in closed position, said disconnect contact being in series with said main and arcing contacts when in closed position; said movable contacts being operable from closed to open position in a predetermined sequence with the main contact opening first, the arcing contact opening next and the disconnect contact opening last, and an arc extinguishing chamber extending longitudinally along said principal axis, an insulating follower extending from said arcing contact through said arc extinguishing chamber along said principal axis, a member carrying said main movable contact, said member having its main axis coinciding with said principal axis; said member housing said arcing contacts and arc extinguishing chamber, said movable disconnect contact when engaged with its complementary contact being in latched engagement with said last-mentioned member; the complementary contact for the disconnect contact being mounted on said member; operating mechanism connected to and moving said movable disconnect contact and being operable through said latch mechanism to draw said last-mentioned member toward open circuit position at said main contacts; and means at said complementary main contact for retaining said movable arcing contact stationary while said member is drawn toward open circuit position at said main contact and maintaining said arcing contacts in engagement.

10. Switch gear extending longitudinally along a principal axis and comprising a movable main contact, a movable arcing contact, a movable disconnect contact and complementary contacts for each of said movable contacts; said movable contacts being operable along said principal axis; said main contacts and arcing contacts being in parallel when in closed position, said disconnect contact being in series with said main and arcing contacts when in closed position; said movable contacts being operable from closed to open position in a predetermined sequence with the main contact opening first, the arcing contact opening next and the disconnect contact opening last, and an arc extinguishing chamber extending longitudinally along said principal axis, an insulating follower extending from said arcing contact through said arc extinguishing chamber along said principal axis, a member carrying said main movable contact; said member housing said arcing contacts and arc extinguishing chamber, said movable disconnect contact when engaged with its complementary contact being in latched engagement with said last-mentioned member; the complementary contact for the disconnect contact being mounted on said member; operating mechanism connected to and moving said movable disconnect contact and being operable through said latch mechanism to draw said last-

mentioned member toward open circuit position at said main contacts; means at said complementary main contact for retaining said movable arcing contact stationary while said member is drawn toward open circuit position at said main contact and maintaining said arcing contacts in engagement; and a resilient energy storing connection between said movable arcing contact and said member; said energy storing connection being biased to increase the opening force on the movable arcing contact as the member is moved further toward open circuit position.

11. Switch gear extending longitudinally along a principal axis and comprising a movable main contact, a movable arcing contact, a movable disconnect contact and complementary contacts for each of said movable contacts; said movable contacts being operable along said principal axis; said main contacts and arcing contacts being in parallel when in closed position, said disconnect contact being in series with said main and arcing contacts when in closed position; said movable contacts being operable from closed to open position in a predetermined sequence with the main contact opening first, the arcing contact opening next and the disconnect contact opening last, and an arc extinguishing chamber extending longitudinally along said principal axis, an insulating follower extending from said arcing contact through said arc extinguishing chamber along said principal axis, a member carrying said main movable contact, said member having its main axis coinciding with said principal axis; said member housing said arcing contacts and arc extinguishing chamber, said movable disconnect contact when engaged with its complementary contact being in latched engagement with said last-mentioned member; the complementary contact for the disconnect contact being mounted on said member; operating mechanism connected to and moving said movable disconnect contact and being operable through said latch mechanism to draw said last-mentioned member toward open circuit position at said main contacts; means at said complementary main contact for retaining said movable arcing contact stationary while said member is drawn toward open circuit position at said main contact and maintaining said arcing contacts in engagement; and a resilient energy storing connection between said movable arcing contact and said member; said energy storing connection being biased to increase the opening force on the movable arcing contact as the member is moved further toward open circuit position; said energy storing connection disengaging said arcing contact retaining means at the completion of movement of said member and driving said arcing contact out of engagement with its main contact.

12. Switch gear extending longitudinally along a principal axis and comprising a movable main contact, a movable arcing contact, a movable disconnect contact and complementary contacts for each of said movable contacts; said movable contacts being operable along said principal axis; said main contacts and arcing contacts being in parallel when in closed position, said disconnect contact being in series with said main and arcing contacts when in closed position; said movable contacts being operable from closed to open position in a predetermined sequence with the main contact opening first, the arcing contact opening next and the disconnect contact opening last, and an arc extinguishing chamber extending longitudinally along said principal

axis, an insulating follower extending from said arcing contact through said arc extinguishing chamber along said principal axis, a member carrying said main movable contact, said member having its main axis coinciding with said principal axis; said member housing said arcing contacts and arc extinguishing chamber, said movable disconnect contact when engaged with its complementary contact being in latched engagement with said last-mentioned member; the complementary contact for the disconnect contact being mounted on said member; operating mechanism connected to and moving said movable disconnect contact and being operable through said latch mechanism to draw said last-mentioned member toward open circuit position at said main contacts; means at said complementary main contact for retaining said movable arcing contact stationary while said member is drawn toward open circuit position at said main contact and maintaining said arcing contacts in engagement; a resilient energy storing connection between said movable arcing contact and said member; said energy storing connection being biased to increase the opening force on the movable arcing contact as the member is moved further toward open circuit position; said energy storing connection disengaging said arcing contact retaining means at the completion of movement of said member and driving said arcing contact out of engagement with its main contact, and a latch releasing element; said movable arcing contact operating said latch releasing element on completion of opening movement of said arcing contact.

13. Switch gear extending longitudinally along a principal axis and comprising a movable main contact, a movable arcing contact, a movable disconnect contact and complementary contacts for each of said movable contacts; said movable contacts being operable along said principal axis; said main contacts and arcing contacts being in parallel when in closed position, said disconnect contact being in series with said main and arcing contacts when in closed position; said movable contacts being operable from closed to open position in a predetermined sequence with the main contact opening first, the arcing contact opening next and the disconnect contact opening last, and an arc extinguishing chamber extending longitudinally along said principal axis, an insulating follower extending from said arcing contact through said arc extinguishing chamber along said principal axis, a member carrying said main movable contact, said member having its main axis coinciding with said principal axis; said member housing said arcing contacts and arc extinguishing chamber, said movable disconnect contact when engaged with its complementary contact being in latched engagement with said last-mentioned member; the complementary contact for the disconnect contact being mounted on said member; operating mechanism connected to and moving said movable disconnect contact and being operable through said latch mechanism to draw said last-mentioned member toward open circuit position at said main contacts; means at said complementary main contact for retaining said movable arcing contact stationary while said member is drawn toward open circuit position at said main contact and maintaining said arcing contacts in engagement; a resilient energy storing connection between said movable arcing contact and said member; said energy storing connection being biased

to increase the opening force on the movable arcing contact as the member is moved further toward open circuit position; said energy storing connection disengaging said arcing contact retaining means at the completion of movement of said member and driving said arcing contact out of engagement with its main contact, and a latch releasing element; said movable arcing contact operating said latch releasing element on completion of opening movement of said arcing contact, said operating mechanism thereafter drawing said disconnect contact away from its complementary contact while said member remains stationary in the open circuit position.

14. Switch gear extending longitudinally along a principal axis and comprising a movable main contact, a movable arcing contact, a movable disconnect contact and complementary contacts for each of said movable contacts; said movable contacts being operable along said principal axis; operating mechanism, a member carrying said movable main and arcing contacts; a movable disconnect contact unit carrying said movable disconnect contact; the complementary disconnect contact being carried by said member; said operating mechanism being connected to and operating said movable disconnect contact unit; and a latch connection between said movable disconnect contact unit and said member.

15. Switch gear extending longitudinally along a principal axis and comprising a movable main contact, a movable arcing contact, a movable disconnect contact and complementary contacts for each of said movable contacts; said movable contacts being operable along said principal axis; operating mechanism, a member carrying said movable main and arcing contacts; a movable disconnect contact unit carrying said movable disconnect contact; the complementary disconnect contact being carried by said member; said operating mechanism being connected to and operating said movable disconnect contact unit; and a latch connection between said movable disconnect contact unit and said member.

30

16. Switch gear extending longitudinally along a principal axis and comprising a movable main contact, a movable arcing contact, a movable disconnect contact and complementary contacts for each of said movable contacts; said movable contacts being operable along said principal axis; said main contacts and arcing contacts being in parallel when in closed position, said disconnect contact being in series with said main and arcing contacts when in closed position; said movable contacts being operable from open to closed position in a predetermined sequence, the disconnect contacts closing first, the arcing contacts and the main contacts closing thereafter, and an arc extinguishing chamber extending longitudinally along said principal axis, an insulating follower extending from said arcing contact through said arc extinguishing chamber along said principal axis, a member carrying said main movable contact; said member housing said arcing contacts and arc extinguishing chamber.
